Application November 13, 1943, Serial No. 510,204

2 Claims. (Cl. 260—681.5)

1

The present invention relates to improvements in the dehydrogenation of normally gaseous hydrocarbons catalytically in a continuous operation under closely controlled conditions of time, temperature, and pressure, and in particular it relates to a method of quenching the reaction products to prevent decomposition or degradation of desired constituents in the product stream.

In the application of Carl E. Kleiber et al., Serial No. 486,636, filed March 12, 1943 there is described a process and apparatus for dehydrogenating hydrocarbons such as butene, one of the outstanding features of that process being that the dehydrogenation is carried out in the presence of a greater volume of steam than reactants in order to lower the partial pressure of the reactants and thereby counteract the tendency for polymer formation and to otherwise improve the operation.

We are enabled to so operate because we employ a catalyst which is not affected by steam. There also is disclosed in the aforesaid application the feature of two-stage quenching of the hot reaction products, and in this present application we have given a fuller and more comprehensive description of this feature of our invention and are claiming it herein. As will subsequently more fully appear hereinafter, we quench the hot reaction products from said butene dehydrogenation process designed to produce substantial quantities of butadiene in an operation characterized by what might be considered to be three phases, as follows: First, desuperheating of the reaction products issuing from the reaction zone; (2) condensation of the tar-forming and gum-forming constituents; and (3) gas cooling and water condensation.

One important result of this operation is that we avoid simultaneous tar and water condensation with its attendant emulsification problems and the further problem of removing objectionable matter from the water so that it may be discharged into riparian streams. More particularly, we first desuperheat the hot reaction products by an initial water quenching operation followed by abstraction of heat in a waste heat boiler, or the like. We then quench with oil to a point below the dew point of tar components but above the condensation temperature of water and finally after separation of the tar or gummy constituents we cool the gases sufficiently to condense the steam.

It is the main object of our invention therefore to quench hot raw butadiene reaction products with oil under conditions such that tar and

2

gum-forming constituents are condensed, but substantial quantities of steam are not condensed.

A more specific object of our invention is to provide a process for quenching hot reaction products as soon as possible after their formation to prevent their degradation or decomposition, which tends to occur at the high temperature level of their formation, by quenching the products with liquids, including water, by a method which avoids oil-water emulsion formation, and its attendant undesirable consequences.

In the accompanying drawings we have shown in Figures 1 and 2 apparatus in which preferred modifications of our invention may be carried into practical effect.

In describing a method illustrating a preferred modification of our invention, we shall assume that butadiene containing vapors are the reaction products to be cooled and that the same have been formed by dehydrogenation of butene by some suitable method such as that described in the aforementioned application. Hence referring in detail first to Fig. 1, 1 represents the reactor in which the butadiene is formed. We have assumed that the reaction products flow downwardly through the reactor containing the catalyst and are withdrawn from the bottom through a pipe 5. Just prior to withdrawal of the reaction products and immediately after their issuance from contact with the catalyst, they are quenched within the reactor by the injection of liquid water at ordinary atmospheric temperature through a line 3 projecting into the reactor and releasing the water through nozzles 4 or any other suitable distributing device. The reaction products are cooled by the water quench just now referred to from a temperature of approximately 1100 to 1250° F. to a temperature within the range of from about 900° to 1000° F. The purpose of this original quench, accomplished virtually at the moment of the egress of the vapors from the catalytic zone, is to reduce the temperature of the reaction products containing butadiene to a temperature level at which the tendency for polymerization to occur is greatly minimized, and, as indicated, this water quench is accomplished immediately so as to reduce rapidly the reaction temperature.

Thereafter, in order to recover for some useful purpose a substantial quantity of the sensible heat contained in the reaction vapors, the same are passed from line 5 through a waste heat boiler 10 where the temperature of the vapors is reduced to temperatures within the range of

from about 500° to 600° F. and, of course, the heat represented by this temperature reduction may be utilized to improve the economics of the process.

The next phases of our operation involve two-stage quenching, in the first stage of which the vapors are quenched with an oil to a temperature which is sufficiently low to permit condensation of oils and tarry products but high enough to prevent substantial condensation of steam. Toward this end, therefore, we withdraw the cooled vapors from waste heat boiler 10 at a temperature of from 500° to 600° F. as previously stated, and discharge them through line 11 into a quench tower 20 where they are quenched with an oil such as a heavy gas oil obtained from catalytic cracking or a pressed oil injected through lines 12 and 65 into line 11 and forced with the reaction products through line 66 into the quench tower as indicated in the drawings. As an alternative the quench oil may preferably be discharged through line 64 into the top of the oil quench tower and over suitable contacting means such as the three bubble cap trays shown in the drawings. The cold oil which is at about atmospheric temperature in line 12 serves to cool the reaction products to a temperature of about 300° F. whereupon they are withdrawn through line 25 and passed to a second and final cooling stage which shall be described presently. The bottoms constituting the quench oil are withdrawn from the tower 20 through line 30, thence pumped by pump 32 through a heat exchanger 35 and thence recycled via line 12 at the temperature previously indicated to the quench tower 20. In quench tower 20, during the operation we have just now described, oil and tarry polymers are condensed and to remove these from the system we provide for them a draw-off line 40. A corresponding amount of clean purging oil is introduced into the circulatory system through line 45.

Referring again to the reaction products in line 25, the same are discharged into the heat exchanger 50 where their temperature is reduced to about 185° F. and thence they are discharged by line 52 into a water quench tower 55. Overhead from water quench tower 55, the butadiene-containing product is withdrawn through line 60 and delivered to storage (not shown). Cooling water is charged to the top of the water quench tower through line 68 and this cooling water together with the steam it condenses are withdrawn from the water quench tower 55 through line 62 and the said water and condensate are substantially free of tarry polymers or other contaminants which would make it an undesirable waste liquor to discharge into a natural stream or river. Minor quantities of light gas oil may condense in the tower 55 but they do not emulsify with the water. They form a separate layer which may be drawn off through line 63.

We shall not describe a method of purifying the butadiene nor have we illustrated this procedure in the drawings because those features do not go to the heart of our invention. Numerous processes are available for treating the raw butadiene with suitable selective solvents to extract it from unconverted butylenes and other contaminating normally gaseous hydrocarbons. Not shown in the drawings are stripping means of any suitable type well known to the art which may be employed to strip and vaporize any butadiene in the oil withdrawn through line 40 and the water withdrawn through line 62. The butadiene thus vaporized is returned as a vapor to the

bottom of oil quench tower 20 or water quench tower 55 respectively.

As to the internal design of the oil quench tower 20 this can be advantageously modified according to circumstances. Thus, for example, a conventional countercurrent tower with bell cap plates has been successfully employed, giving great intimacy of contact and a close control over the final temperature of the gaseous product. Baffle plates, especially of the disc and doughnut type, may be substituted for the bell cap plates; and it will be desirable to do so in cases where tars and polymers tend to deposit and to block up the narrower passages of the bell caps. In certain cases where it becomes particularly desirable to avoid overheating of the liquid phase, and the resulting polymerization of dissolved tar forming components, a concurrent downward flow over disc and doughnut baffles will become desirable. The downward concurrent flow is accomplished by introducing hot gases from the preliminary cooling step into the top of the oil quench tower, immediately causing the hot gases to mix with cold quench oil also introduced at the top, and causing the mixture of gas and liquid to flow downward through disc and doughnut plates until the mixing is substantially complete and the gases are cooled to a temperature approaching the condensation point of water.

In Fig. 2 we have shown a second exemplification of our invention, and at the outset we wish to point out that in this exemplification the essential difference from the exemplification of Fig. 1 is that in the oil quenching zone, the flow of gaseous reaction products is concurrent downward with the quenching medium. Actually we have shown concurrent downward flow of gaseous reaction products and liquid quenching medium, but concurrent upward flow is also within the scope of our invention. Another feature of the modification shown in Fig. 2 is the fact that in the oil quenching zone, the oil flows through tubes around which cooling water circulates so that the metal within the quenching zone is continuously cooled.

Referring in detail to Fig. 2, we shall assume that the butadiene-containing vapors to be quenched have undergone the original quenching described in Fig. 1 and the sensible heat abstracted to the point where the vapors are cooled in line 11 of Fig. 1 to a temperature of 500° to 600° F. In Fig. 2, the vapors in line 11—a therefore are at about the same temperature as the vapors in line 11 of Fig. 1, that is, somewhere in the range of from 500°—600° F. At this temperature we inject water into the vapor line 11—a from line 7—a, this water being at a temperature of about atmospheric and thereafter the vapors are discharged into an oil quenching zone 20—a where it is mixed with oil introduced through line 12—a and spray from nozzle 10. The quenching zone 20—a contains a bank of tubes 100 terminating in tube sheets 101, the tubes being in communication with the spaces above and below the said tube sheets. The mixture of quenching oil, water and hot gases pass concurrently downward through the tubes 100 and at the same time indirect cooling water is injected via line 111 into the space between the tube sheets and surrounding the bank of tubes, the cooling water being withdrawn from 20—a through line 112. The quenched vapors and quenching oil are withdrawn from quenching zone 20—a through line 102 and discharged into a separator 104 from which condensed tar may be withdrawn through line 160.

carrying pump 162 and then rejected from the system through line 180. Where gas oil is used to quench the vapors, and where it is not too contaminated with tar, a portion of the oil in line 180 may be recycled through line 165 to coolers 5 170 and line 171 to line 12-a for further use in the process.

Referring again to the separator 104, it is pointed out that the liquid is maintained at a fairly constant temperature of around 250° F. 10 To insure this temperature, I provide communication between the outlet line 171 from the gas oil and tar coolers 170 by means of a line 205 carrying flow control valve 206 which operates responsive to the temperature in 104 so as to admit cold oil to 104 automatically, to maintain the temperature level indicated. The overhead line 115 contains the gases, namely the butadiene and steam, which are separated from the condensate in 104 and these are discharged into a 20 second oil quenching zone 20-b, also fed with quenching oil from 12-b in precisely the same manner as in 20-a, and the cold oil flows downwardly through the tubes around which cooled water from 110 circulates, and the gases are further cooled and quenched and eventually withdrawn through line 102-a and discharged into a second separator 104-a. As before, the separation is effected between the oil and the gases and the former is withdrawn through line 160-a 30 carrying pump 162-a, by means of which the oil may be pumped from the system through line 180-a or recycled in part through line 165, as previously indicated.

With respect to the gases in separator 104-a, 35 the same may be withdrawn through line 120, passed through coolers 122 and thence discharged into receiving drum 130 which we have shown tilted, via line 125. In the gas coolers 122 the steam is condensed together with light naphtha, and these condensates stratify in receiving drum 130, the water of course forming the lower layer, and this may be withdrawn through line 142 and rejected from the system through line 143. This water is substantially unpolluted with tar and gummy constituents and may be discharged into natural streams or rivers. A portion of this water may be pumped by pump 200 and line 201 to the aforementioned line 1-a, which it will be recalled was a line supplying quench water to the vapors about to enter the first oil quenching zone.

Referring again to receiving drum 130, the naphtha may be withdrawn through line 140 and rejected from the system. The butadiene-containing product is withdrawn from line 160 and thereafter purified by means not shown, since the solvent extraction and other conventional means of purifying butadiene do not go to the heart of this present invention.

Instead of causing the vapors and oil to flow concurrently downward in the quenching zones 20-a, the same may be caused to flow in such a manner that a portion of the vapors flow concurrently with the oil, while another portion flows counter-currently with the oil. We have not illustrated this modification of our invention in the drawings because suitable apparatus for accomplishing this result will be apparent to those

familiar with the art in view of preceding description.

While we have described our invention in terms of butadiene quenching immediately following its formation during dehydrogenation of butenes it will be understood that our improvements are applicable to the quenching of any gaseous and/or vapor product rapidly and immediately after its formation. In other words, our improvements are applicable broadly to the rapid quenching of newly formed reaction products which are at high temperatures and which are apt to undergo degradation with consequent loss in yield to a point where such degradation is greatly minimized. And more specifically, an important phase of our invention involves the quenching of oily material or hydrocarbon material at high temperatures admixed with water under conditions such that the main body of the water is condensed uncontaminated with substantial quantities of oily material or with merely minor quantities of light oily material and substantially free of tarry and heavy material.

What we claim is:

1. In the production of diolefins by catalytic dehydrogenation of relatively more saturated hydrocarbons in the presence of steam to form a gaseous product stream containing said diolefin, steam and unstable tar-forming and gum-forming impurities, an improved method of cooling said product stream to prevent degradation of the desired diolefin, comprising withdrawing said product from the reaction zone, immediately injecting water into said product to cool it quickly to a temperature of 900 to 1000° F., then cooling the product by indirect heat transfer to a temperature of 500 to 600° F., then further cooling the product by direct contact with a liquid hydrocarbon oil to a temperature of about 300° F. to remove said tar-forming and gum-forming impurities, then further cooling said product to condense steam therefrom by direct contact with liquid water, and thereafter separating the resulting diolefin-containing product from the water condensate.

2. In the production of butadiene by catalytic dehydrogenation of normal butenes in the presence of steam to produce a gaseous product stream containing butadiene, steam and unstable tar-forming and gum-forming impurities, an improved method of cooling said product stream, comprising withdrawing said product from the reaction zone, immediately injecting water into said product to cool it quickly to a temperature of about 900 to 1000° F., then cooling the product by indirect heat transfer to a temperature of about 500 to 600° F., then further cooling the product by direct contact with a liquid hydrocarbon oil to a temperature of about 300° F. to remove said tar-forming and gum-forming impurities, then further cooling said product to condense steam therefrom, and thereafter separating the resulting butadiene-containing product from the water condensate.
